UNITED STATES PATENT OFFICE

158,516

CHESS PIECE

Seymour C. Schlossberg, Chicago, Ill.

Application November 16, 1948, Serial No. 149,655

Term of patent 14 years

(Cl. D34—5)

To all whom it may concern:

Be it known that I, Seymour C. Schlossberg, a citizen of the United States, residing at Chicago, in the county of Cook and State of Illinois, have invented a new, original, and ornamental Design for a Chess Piece, of which the following is a specification, reference being had to the accompanying drawing, forming part thereof.

Fig. 1 is an elevational view from one side of a chess piece, showing my new design;

Fig. 2 is a front elevational view, omitting the dotted line showing of the base;

Fig. 3 is an elevational view from the other side thereof, omitting the dotted line showing of the base; and

Fig. 4 is a rear elevational view, omitting the dotted line showing of the base.

The characteristic features of my design reside in the portions shown in full lines.

I claim:

The ornamental design for a chess piece, as shown and described.

SEYMOUR C. SCHLOSSBERG.
